UNITED STATES PATENT OFFICE.

JAMES CRAWFORD, OF ROXBURY, MASSACHUSETTS, ASSIGNOR TO JOSEPH H. YOUNG CO., OF BOSTON, MASSACHUSETTS, A CORPORATION OF MASSACHUSETTS.

DESIGN FOR A BATH-TUB TRAP.

45,253.

Specification for Design.

Patented Feb. 17, 1914.

Application filed June 16, 1913. Serial No. 774,043. Term of patent 7 years.

To all whom it may concern:

Be it known that I, JAMES CRAWFORD, a citizen of the United States, residing at Roxbury, in the county of Suffolk and State of Massachusetts, have invented a new, original, and ornamental Design for Bath-Tub Traps, of which the following is a specification, reference being had to the accompanying drawing, forming part thereof.

The figure is a perspective view of a bath tub trap showing my new design, the essential features of which comprise the body portion circular in cross section, rounded at each end and provided with four openings

or upwardly projecting portions arranged at different elevations from the body, the upwardly projecting portion on one end being of greater length than the other projecting portions and having attached thereto a collar or sleeve having a laterally projecting flange portion.

I claim:

The ornamental design for a bath tub trap, as shown and described.

JAMES CRAWFORD.
